UNITED STATES PATENT OFFICE.

LAURENCE E. TOPHAM, OF SWAMPSOFT, MASSACHUSETTS, ASSIGNEE TO UNITED SHOE MACHINERY COMPANY, OF PATERSON, NEW JERSEY, A CORPORATION OF NEW JERSEY.

CHAIN-STITCH INSEAM SHOE-SEWING MACHINE.

1,241,785.

Specification of Letters Patent.

Patented Oct. 2, 1917.

Application filed January 24, 1916. Serial No. 73,882.

To all whom it may concern:

Be it known that I, LAURENCE E. TOPHAM, a citizen of the United States, residing at Swampscott, in the county of Essex and State of Massachusetts, have invented 5 certain new and useful Improvements in Chain - Stitch Inseam Shoe - Sewing Machines, and I do hereby declare the following to be a full, clear, and exact description 10 of the invention, such as will enable others skilled in the art to which it appertains to make and use the same.

The present invention relates to chain stitch inseam shoe sewing machines which 15 employ a curved hook needle and which are used to sew together the upper and insole of turn shoes, or the welt, upper and insole of welted shoes.

After the inseam of a shoe has been sewed 20 on a machine of the class above referred to the last loop of thread drawn through the work by the needle must be freed from the needle hook and the needle must be brought to rest out of engagement with the work before the shoe can be removed from the machine.

The object of the present invention is to 25 provide novel and efficient means for performing these operations automatically as the machine is stopped.

In an application, Serial No. 73,881, filed January 24th, 1916, I have disclosed and claimed mechanism embodied in a machine of the class referred to which operates automatically upon stopping the machine to perform these operations. The invention disclosed in that application, broadly considered, contemplates advancing the needle 35 from its retracted position as the machine is stopped until the thread is freed from the hook or barb of the needle and bringing the needle to rest in advanced position out of engagement with the work. With the specific mechanism described in that application these operations involve a reversal in 40 the direction of rotation of the cam shaft of the machine. The reversal in the direction of rotation of the cam shaft not only necessitates stopping the forward rotation 45 of the cam shaft, turning it backward and again stopping it in predetermined position, but also necessitates stopping the machine in a position in which both the back rest and the welt guide are locked in engagement 50 with the shoe. The present invention con-

templates the provision in a machine of the class above referred to of means which will act automatically as the machine is stopped and during the continued forward rotation of the cam shaft to advance the needle from 60 its retracted position, to free the needle hook or barb from the thread and bring the needle to rest in advanced position out of engagement with the work. By advancing the needle toward the work during the continued forward rotation of the cam shaft 65 and by stopping the needle in advanced position out of engagement with the work the barb of the needle is freed from the thread as effectively as when the advancing movement of the needle is produced by a reversal in the direction of rotation of the cam shaft. Also, the other parts of the machine are stopped in a position in which the work can be more readily removed from 70 the machine. However, in curved hook needle inseam shoe sewing machines as usually constructed an advancing movement towards the work is imparted to the welt guide or back rest during the work piercing 75 stroke of the needle and in applying the present invention to an inseam shoe sewing machine of well-known construction it has been found that during the advancing movement of the needle to free the thread from 80 the barb as the machine is stopped the welt guide or back gage advances partway toward the shoe. To facilitate the removal of the shoe from this machine it is desirable that a retracting movement be imparted to 85 the welt guide or back rest as the machine is stopped, and accordingly a further feature of the invention contemplates the provision of means for securing this result.

The present invention will be clearly understood from an inspection of the accompanying drawings in which the preferred embodiment of the invention is illustrated as applied to a welt shoe sewing machine 90 of well-known construction.

Referring to the drawings; Figure 1 is a view in side elevation of the complete machine; Fig. 2 is a view in side elevation, partly in section of the head of the machine; Fig. 3 is a plan view partly in section of a portion of the head of the machine illustrating the mechanism by means of which an advancing movement from its retracted position is imparted to the needle during the continued forward rotation of 110

the cam shaft as the machine is stopped and the needle is brought to rest in advanced position out of engagement with the work; Fig. 4 is a detail view in side elevation partly in section of a portion of the head of the machine illustrating particularly the mechanism by which the welt guide is retracted as the needle comes to rest in advanced position; Fig. 5 is a detail view in front elevation partly in section of the parts illustrated in Fig. 4; Fig. 6 is a detail sectional view of a portion of the head of the machine illustrating another part of the welt guide retracting mechanism; Fig. 7 is a detail view in rear elevation of the parts illustrated in Fig. 6; and Figs. 8 and 9 are somewhat diagrammatic detail views illustrating the action of the needle in freeing the thread from the needle hook or barb when the machine is stopped, Fig. 8 illustrating the manner in which the needle loop is held in the barb of the needle when the needle is at the limit of its retracting stroke, and Fig. 9 illustrating the manner in which the needle loop has been freed from the barb of the needle after the needle has been advanced and brought to rest in advanced position out of engagement with the work. In Fig. 8, for the sake of clearness, the rear or work side of the needle loop is shown displaced somewhat from the position which it actually assumes when the needle is retracted.

The welt shoe sewing machine illustrated in the drawings, except as hereinafter described, is the same in the construction, arrangement and mode of operation of its parts as the machine disclosed in the patent to Eppler, No. 1,108,560, dated August 25, 1914. Referring to Fig. 2 of the drawings the curved hook needle of the machine is indicated at 1, the looper at 2, the thread arm at 3, the welt guide at 4, the welt guide slide at 5, the back rest or bunter at 6, the thread tension devices at 7, the cam shaft at 8, and the tension releasing lever which is actuated to release the tension on the thread when the machine stops, at 9. During the operation of the machine the cam shaft 8 is driven continuously by means of a belt 10 passing over a pulley 11 on the cam shaft and over a pulley 12 secured to a shaft 13 mounted in the base of the machine. The shaft 13 is connected by bevel gears 14 and 15 to a sleeve mounted on the power shaft 16 of the machine and provided with one member 17 of a friction clutch. The other member 18 of the friction clutch is splined on the shaft 16 so as to rotate therewith and is acted upon by a spring 19, the tendency of which is to separate the clutch members. The clutch member 18 is arranged to be acted upon by a wedge 20 which is connected to a foot treadle 21, the arrangement being such that by means of the foot treadle 21 and wedge 20 the speed of the machine can be regulated

and the machine can be disconnected from its driving power and allowed to stop by a total release of the treadle 21.

The machine illustrated in the drawings is provided with means whereby when the treadle 21 is released to stop the machine, the needle is brought to its retracted position, as indicated in Fig. 8, and then during the continued forward rotation of the cam shaft, is advanced toward the work, as indicated in Fig. 9, and brought to rest in this advanced position out of engagement with the work. The result of this movement of the needle frees the last loop of needle thread from the barb of the needle, as indicated in Fig. 9, and leaves the needle and thread in such position that the shoe can immediately be removed from the machine without any further manipulation of the machine by the operator.

The mechanism illustrated in the drawings for advancing the needle from its retracted position toward the work and bringing it to rest in advanced position out of engagement with the work is mounted in the head of the machine and acts upon the cam shaft 8. This mechanism includes a friction clutch mounted on the cam shaft of the machine, one member of which is constantly driven in the same direction as the cam shaft. This friction clutch when thrown into operation acts first as a friction brake to slow down the cam shaft and then continues the forward rotation of the cam shaft. The mechanism for advancing the needle and bringing it to rest out of engagement with the work as the machine is stopped also includes devices for throwing the friction clutch into and out of operation and for stopping the cam shaft in a predetermined position.

The friction clutch above referred to comprises a continuously rotating clutch member 22 mounted loosely on the cam shaft 8 and a co-operating member 23 mounted to rotate with the cam shaft. The clutch member 22 is rigidly connected with a worm gear 24 which is constantly driven in the same direction as the cam shaft 8 by means of a worm 25 the shaft of which is provided with a pulley 26 driven through a belt 27 from a pulley 28 on the power shaft 16 of the machine. The clutch member 23 is provided with a hub 29 which is connected to rotate with the belt pulley 26 by means of a block 30 projecting from the pulley between lugs 31 on the hub 29. This connection causes the clutch member 23 to rotate with the cam shaft, but permits a movement of the clutch member longitudinally of the cam shaft toward and from the clutch member 22. During the normal operation of the machine in sewing a seam the clutch member 23 is held out of engagement with the clutch member 22 by means of a spring 32. This spring is

interposed between the head of a pin 33 and the bottom of a recess in the block 30. The pin 33 extends through the block 30 and is provided on its inner end with a plate 34 overlapping the projections 31 from the hub 29 of the clutch member 23. To cause the clutch member 23 to be moved into and out of engagement with the clutch member 22 the hub 29 of the clutch member 23 is provided with a cam groove 35 which is engaged by a roll on one end of a bell crank lever 36 pivotally mounted on the frame of the machine. The other end of the bell crank lever is provided with a hole 37, see Fig. 7, adapted to receive a locking bolt 38, which while the machine is sewing a seam is held out of engagement with the bell crank lever so that the bell crank lever is oscillated idly by the cam and groove and the clutch member 23 remains out of engagement with the clutch member 22. When, however, the treadle 21 is allowed to rise, the bolt 38 is permitted to engage the hole in the bell crank lever 36. The release of the treadle 21 releases the driving clutch disks 17 and 18 so that the machine is disconnected from its driving power and at the time the bolt 38 engages the bell crank 36 the cam shaft 8 of the machine is turning forward under 8 of the machine is turning forward under 30 momentum. The continued forward rotation of the cam shaft 8 causes the cam groove 35 to force the clutch member 23 into engagement with the clutch member 22. After the clutch member 23 is engaged with clutch member 22 the cam shaft is slowed down and then driven forward at reduced speed until the cam groove 35 acting on the roll in the arm of bell crank 36 moves the clutch member 23 out of engagement with 35 the clutch member 22. The clutch member 23 is disconnected from the clutch member 22 just before the needle reaches the position indicated in Fig. 9.

The locking pin 38 is mounted in the end 40 of a slide 39 which is held in normal position by a spring 40. The spring surrounds a bolt 41 extending from the rear end of the slide and is interposed between a shoulder on the slide and the inner end of an adjustable screw threaded sleeve 42. The bolt 41 extends through a fixed bracket 43 and carries a nut 44 which engages the outer side of the bracket 43 so as to hold the spring 40 under tension. The locking bolt 38 is acted upon by a spring 45 which tends to raise it into engagement with the bell crank lever 36 and the bolt is provided with a latch 46 arranged to engage a shoulder 47 on the slide 39 and hold the bolt in its lower position until the treadle 21 has been raised sufficiently to allow the locking bolt to engage the bell crank lever. The latch 46 is loosely pivoted upon a rock shaft 48 journaled in a block secured to the lower end of the locking bolt 38 and is connected to the rock shaft by

a pin 49 projecting through a slot in the hub of the latch. The rock shaft 48 is provided with an arm 50 which is connected by a rod 51 to the starting and stopping treadle 21. With this construction, when the treadle 21 is depressed the rock shaft 48 turns until the latch 46 brings up against the slide 39 and then during the continued downward movement of the treadle the locking bolt is drawn down against the tension of its spring. This carries the latch 46 under the shoulder 47. When the treadle is released the latch 46 prevents the upward movement of the locking bolt and the rock shaft 48 is rocked until the pin 49 strikes the end of the slot in the hub of the latch and swings the latch outward, thus disengaging it from the shoulder 47. When this takes place the spring 45 forces the locking bolt upward against the under side of the bell crank lever 36 and when the hole in the lever registers with the locking bolt the bolt snaps up into the hole 37, thus connecting the bell crank lever with the slide 39. When the bell crank lever 36, and the slide 39 are connected by the locking bolt the movement of the bell crank lever is resisted by the spring 40 and the clutch members 23 and 22 are pressed together with a force depending upon the tension of the spring 40.

In the machine illustrated in the drawings the welt guide has advanced partway toward the shoe by the time the needle reaches the position indicated in Fig. 9. To facilitate the removal of the shoe, means are provided whereby as the machine is brought to rest with the needle in the position indicated in Fig. 9, the welt guide is retracted. As has been described the final forward movement of the needle and the bringing of the needle to rest in the position indicated in Fig. 9 is accomplished by connecting the bell crank lever 36 and the slide 39. When these parts are connected the friction clutch members 23 and 22 are brought into engagement and during the continued rotation of the cam shaft a reciprocating movement is imparted to the slide 39 and bolt 41, a forward movement being imparted to the slide by the action of the cam groove 35 and a return rearward movement by the action of the spring 40. In the machine illustrated in the drawings this reciprocatory movement of the slide 39 and bolt 41 is utilized to retract the welt guide. The mechanism for actuating the welt guide during the normal operation of the machine in sewing a seam comprises a clutch box 52 through which the welt guide slide 5 passes, a cam actuated lever 53, and a link 54 connecting the lower end of the lever 53 with the clutch box 52. The clutch box 52, connecting link 54, and the lower end of the lever 53 are constructed and arranged to operate in the same manner as

the corresponding parts disclosed in the patent to Eppler hereinbefore referred to. The mechanism for actuating the lever 53 during the normal operation of the machine 5 in sewing a seam consists of a cam actuated lever 55 pivoted upon the upper arm of the lever 53, a toggle consisting of the links 56 and 57 connecting the upper end of the lever 53 with the vertical arm of the tension releasing lever 9 and a link 58 connecting the central point of the toggle with the lever 55. During the normal operation of the machine in sewing a seam with the parts in the position indicated in Fig. 2 the lever 10 9 is held stationary and during each rotation of the cam shaft 8 the toggle 56-57 is actuated to oscillate the lever 53. During the final cycle of operations, however, after the treadle 21 has been released to 15 stop the machine the vertical arm of the lever 9 is moved backwardly to the position indicated in Fig. 6 and this movement of the arm acting through the links 56, 57 and 58, causes the welt guide to be retracted so as not to be in a position to interfere with the removal of the shoe when the needle stops in the position indicated in Fig. 9. To utilize the reciprocating movements of 20 the slide 39 to oscillate the lever 9 on stopping the machine a link or bar 59 is pivotally connected at its rear end to the upper end of the lever 9 and at its forward end is provided with a bell crank lever 60. The 25 horizontal arm of this bell crank 60 is provided with a slot which engages a pin projecting from the upper end of an arm 61 the hub 62 of which is journaled on a pin 63 secured in the frame of the machine. The vertical arm of the bell crank 60 is 30 connected by a spring 64 to the arm 61. The hub 62 is provided with a second arm 65 provided at its upper end with a slot in which is seated a block mounted upon a pin 66 carried by a block 67 secured to the 35 outer end of bolt 41 between the nut 44 and a nut 68. In the normal position of the parts, while the machine is running, as indicated in Fig. 2, the pin in the upper end of arm 61 presses against the end of the slot 40 in bell crank 60 and holds the bell crank and the link 59 in the position indicated in Fig. 2, the spring 40 which acts on the slide 39 being sufficient to overcome spring 64 which acts on bell crank 60. When, however, the slide 39 moves forwardly during 45 the final cycle of operations of the machine the hub 62 is rocked through the arm 65 and the pin in the upper end of arm 61 is moved outwardly in the slot of bell crank 60 so that the spring 64 acting on the bell 50 crank is permitted to swing the parts into the position indicated in Fig. 4. With

the parts in this position the horizontal arm of bell crank 60 is substantially in alignment with the link 59 so that when 65 the slide 39 is returned to its original position by the spring 40 the link 59 is moved endwise and the lever 9 is moved to the position indicated in Fig. 6.

In the machine illustrated in the drawings the lever 9 is also utilized to apply a brake to the cam shaft. As shown, the brake consists of a brake band 69 arranged to act on a disk secured to the cam shaft. One end of this brake band is secured to 70 the stud 63 and the other end is secured to an eccentric 70 formed on the stud 71 which forms the pivotal connection between the link 59 and the lever 9. To release the brake band by the downward movement of 75 the starting treadle so that the brake may be removed before the machine is started the stud 71 is provided with a slotted arm 72 which is engaged by the pin 73 which forms the pivotal connection between the 80 arm 50 and the rod 51.

To return the lever 9 to the position indicated in Fig. 2 and also to cause the link 59 and bell crank 60 to assume the position indicated in Fig. 2 the cam shaft of the 90 machine is provided with a cam 74 which during the first rotation of the cam shaft after the machine is thrown into operation engages and lifts the link 59.

The nature and scope of the present invention having been indicated and the preferred form of the invention having been described, what is claimed is:—

1. An inseam shoe sewing machine, having in combination, stitch forming mechanism including a curved hooked needle, a looper and devices coöperating therewith to form a chain stitch seam, and means operating automatically on stopping the machine to continue the forward rotation of the cam shaft 100 to advance the needle from its retracted position to free the hook from the last needle loop and bring the needle to rest in advanced position out of engagement with the work.

2. A chain stitch inseam shoe sewing machine, having in combination, stitch forming devices including a curved hooked needle and a looper, a work guide, means operating automatically on stopping the machine to continue the forward rotation of the cam shaft to advance the needle from its retracted position to free the hook from the last needle loop and bring the needle to rest in advanced position out of engagement with the work, and means thrown into operation on stopping the machine for retracting the work guide.

LAURENCE E. TOPHAM.
